UNITED STATES PATENT OFFICE.

JAMES T. ROBB, OF BROOKLYN, NEW YORK, ASSIGNOR TO THE MITCHELL VANCE COMPANY, OF NEW YORK, N. Y., A CORPORATION OF NEW YORK.

CEILING OR WALL BOX.

SPECIFICATION forming part of Letters Patent No. 727,842, dated May 12, 1903.

Application filed November 12, 1902. Serial No. 130,966. (No model.)

To all whom it may concern:

Be it known that I, JAMES T. ROBB, a subject of the King of Great Britain, residing at Flatbush, in the borough of Brooklyn, city of 5 New York, State of New York, have invented a certain new and useful Improvement in Ceiling or Wall Boxes, of which the following is a description.

My invention relates to improvements in 10 ceiling and wall boxes for electric-light fixtures, and has for its object to produce a device of the type employing an ordinary ceiling or wall box, (or "junction-box," as it is commonly called,) having mounted therein 15 an insulated nipple for the support of the electric-light fixture, thereby doing away with the objectionable insulating-joint and making the device extremely simple, durable, and inexpensive.

20 In order that the invention may be better understood, attention is directed to the accompanying drawings, forming a part of this specification, and in which—

Figure 1 is a vertical section through a junction-box embodying my present improvements, and Fig. 2, a section on the line 2 of Fig. 1.

In both of the views corresponding parts are represented by the same numerals of reference.

The box 1 is made as heretofore, preferably of cast-iron, and is provided with a cover 2, having an opening therein through which passes the fixture. The top of the box is cast 35 with an integral tapering sleeve 3, square in cross-section (see Fig. 2) and having a countersunk portion 4 for receiving a plate 5, adapted to be screwed in place. The nipple is provided with a wedge-shaped head 6, fitting 40 into the sleeve 3 and insulated therefrom in any suitable way, preferably by means of four pieces of insulating material 7. Above the head 6 is placed a layer of insulation 8, so that by screwing the plate 5 tightly in place 45 the parts will be held snugly in position within the sleeve 3. Below the sleeve 3 is a layer of insulation 9, surrounding the nipple and held in place by a nut or threaded washer 10, engaging the threads of the nipple. Above 50 the insulating layer 9 and supported by the same is a collar 11, of insulating material,

which surrounds the sleeve 3 and insulates the same. This collar is held snugly in place by forcing home the nut 10, as will be understood.

The broadest features of the invention are not claimed in the present application, which relates to a joint formed integrally with a wall of the junction-box. The joint *per se* is to form the subject-matter of and be claimed in 60 an application for patent to be made subsequently. (Serial No. 133,878, filed December 4, 1902.)

Having now described my invention, what I claim is—

1. As a new manufacture, a ceiling or wall box formed with an integral tapering sleeve in its top, and a nipple depending from said sleeve and having a wedge-shaped head engaging the same, with insulating material between the nipple and sleeve, substantially as set forth.

2. As a new manufacture, a ceiling or wall box formed with an integral tapering sleeve in its top, a nipple depending from said sleeve and having a wedge-shaped head engaging the same, with insulating material between the nipple and sleeve, and a plate secured to the top of the box above said head, substantially as set forth.

3. As a new manufacture, a ceiling or wall box formed with an integral tapering sleeve in its top, a nipple depending from said sleeve and having a wedge-shaped head engaging the same, with insulating material between 85 the nipple and sleeve, and a countersunk plate secured to the top of the box above said head, substantially as set forth.

4. As a new manufacture, a ceiling or wall box cast with an integral tapering sleeve, a 90 nipple depending from said sleeve and having a wedge-shaped head engaging the same, insulating material between the nipple and sleeve, and an insulating-collar surrounding the sleeve, substantially as set forth.

5. As a new manufacture, a ceiling or wall box cast with a tapering sleeve, a nipple depending from the sleeve and having a wedge-shaped head which engages the sleeve, insulating material between the head of said 100 nipple and the sleeve, a layer of insulating material surrounding the nipple and engaging

the bottom face of the sleeve, and a threaded nut on the nipple for holding said insulating layer in position, substantially as set forth.

6. As a new manufacture, a ceiling or wall box cast with a tapering sleeve, a nipple depending from the sleeve and having a wedge-shaped head which engages the sleeve, insulating material between the head of said nipple and the sleeve, a layer of insulating material surrounding the nipple and engaging the bottom face of the sleeve, a threaded

nut on the nipple for holding said insulating layer in position, and an insulating collar supported by the insulating layer and surrounding the sleeve, substantially as set forth. 15

This specification signed and witnessed this 11th day of November, 1902.

JAMES T. ROBB.
